UNITED STATES PATENT OFFICE.

EUGENE J. WITCHGER, OF SAGINAW, MICHIGAN, ASSIGNEE TO LUFKIN RULE CO., OF SAGINAW, MICHIGAN, A CORPORATION OF MICHIGAN.

CASE FOR TAPE MEASURES.

Application filed October 3, 1927. Serial No. 223,523.

This invention is a case for tape measures and pertains to that general type of tape measure case now in common use, in which the tape is enclosed by a pair of disk-like metal covers, which in turn are overlaid by a covering of leather, fabric or similar material. In United States Patent No. 1,609,852 issued to me December 7, 1926 I showed and described a construction and arrangement in which the flanges of the disk-like covers are held in spaced relation by a circular rim made of sheet metal and having its edges slightly flanged to grip the outer edges of the case members to keep them from moving apart, and also having an internal bead received between the spaced edges of the disk flanges, thereby holding these flanges immovable toward each other.

That patent also discloses a two-part fabric cover, the marginal edges of which are seated in the groove formed by the internal bead. The structure of the patent includes a hoop-like band received in the groove and clamping the marginal edges of the covers in place, the ends of the hoop being anchored to the case in any suitable manner. In the structure of that patent, as in other tape measure cases of the same general character, the hoop-like binding action of the band in the groove is what holds the fabric in place.

My present invention relates to an improved bead construction by which the marginal edges of the fabric cover are pinched, gripped or clamped in the groove formed by the bead, as distinguished from what may be termed the hoop tensioning method disclosed in the previous patent.

In my improved bead construction the edges of the covers are clamped around the periphery of the case by means of a bead characterized by having its side and bottom walls flexible or collapsible, that is to say, capable of being deformed by pressing, rolling or squeezing them together. The walls of the bead are thereby made to bulge so as to project into engagement with the interior faces of the disked flanges, locking the sheet metal rim to the periphery of the case and making it optional instead of absolutely necessary, as heretofore, to provide a hoop-like band to clamp the edges of the fabric. Such a band, however, can, if desired, be used for purposes of rim reinforcement or for ornamental appearance. In the drawings I have illustrated the invention both with an ornamental ring

member inserted in the bead and without one, and also with an entirely concealed reinforcing member.

In the drawings Fig. 1 represents the case partly in edge view and partly in section. 60

Fig. 2 is an enlarged cross sectional view of the binding rim, the bead being represented in full lines in its initial shape and being indicated in dotted lines in its final shape.

Figs. 3, 4, 5 are respectively representations 65 of the binding ring, the cover and the reinforcing band or ring member.

Fig. 6 is a sectional detail representing the said parts assembled.

Fig. 7 represents the assembly before the 70 grooved member or bead of the binding rim is distorted to form the case structure shown in Fig. 8.

Fig. 8 is a sectional detail of a modified form of case structure. 75

Fig. 9 is a further modified form.

Fig. 10 is a still further modified form.

As is clearly shown in the drawings numerals 1 and 2 indicate the pair of disk-like case members which are formed with flanges 80 3, 4 spaced apart. The cover pieces 5, 6 are applied in the usual way. A sheet metal rim 7 having case-gripping edges 8, 8 surrounds the case. The rim 7 also has an internal bead 9 which is received between the spaced edges 85 3^a, 4^a of the flanges 3, 4. The bead 9 in its original shape is shown in Figs. 2 and 7, having the external appearance of a peripheral trough of rectangular or other suitable cross sectional shape that projects into 90 the case. The bead 9 is made of a flexible material, such as sheet brass or soft steel.

In making the case the flanges 3, 4 after assembling as shown in Fig. 7, are forced toward each other into the position shown in 95 Fig. 8. This distorts the bead 9 inside the case and accomplishes two important results. Firstly, it spreads the wall of the bead into clamping engagement with the inner faces of the flanged edges 3^a, 4^a, thereby pinching 100 the rim 7 at all points of its length tightly against the flanges 3, 4. By rolling the bead flat as shown in the drawings there is formed a strong, rigid case that does not depend upon tensioned binding hoop action for its integrity. Secondly, by forcing the side walls of the bead toward each other as shown in broken lines in Fig. 2 the marginal edges of the cover pieces 5, 6 are tightly clamped, i. e. with a ring member such as 10 or 11 in the 110

bead as shown in Figs. 6 and 8, or without it as shown in Figs. 9 and 10. The fabric is securely clamped by the bead walls, regardless of whether the ends of the ring member 10 are fastened to the edges of the tape, opening 12 or not.

In Figs. 7 and 8, a concealed reinforcing ring 11 is shown.

It is now apparent that in the structures 10 above described the edges of the fabric may be clamped tightly around the periphery of the case without using any band that requires to be anchored to the flanges 3, 4 at its ends. In fact it is not essential to the operation of 15 the invention to employ any hoop at all, for example, the structures of Figs. 9 and 10. Moreover, in the structures of Figs. 8 and 9, distorting the bead within the case, so that it projects underneath and engages the interior faces of the flanged edges 3^a, 4^a, locks 20 the parts together and forms a strong, rigid structure, even without the fabric cover pieces 5.

When the fabric covers are employed the 25 distorted bead performs all necessary clamping functions without the aid of a binding hoop.

Having thus described my invention, what I claim and desire to secure by Letters Patent is:

1. A case including flanged side members, a flange-enclosing rim formed with an internal bead that projects between the flanges, a pair 35 of cover members having their edges received in the groove formed by said bead, and the walls of said bead distorted to tightly clamp the edges of said cover members in said groove.

2. A tape measure case comprising a pair 40 of side members having peripheral flanges arranged with their edges directed toward each other and spaced apart, a circumferential band overlying said flanges, its lateral edges shaped to engage the outer shoulders of 45 said flanges to hold the side members against movement away from each other, said band formed with an inwardly projecting flexible bead whose sides, in engagement with the edges of said spaced flanges, hold said flanges 50 immovable toward each other, a two-part

cover whose marginal edges are seated in the groove formed by said bead and are secured therein by the clamping action of the walls of said bead when compressed.

3. A pair of case members formed with 55 opposed flanges spaced apart, cover pieces on said case members, a sheet metal rim having case-gripping edges and also having an internal bead received between the spaced edges of said flanges, exterior parts of the walls of 60 said bead bent to project into engagement with the interior faces of the flanges and interior parts of the walls of said bead in clamping engagement with the marginal edges of 65 said cover pieces.

4. A pair of case members formed with flanges, a sheet metal band enclosing said flanges and having case-gripping edges and formed with a bead, coverings, a ring member received in said bead, said bead shaped 70 to engage the inner faces of said flanges with its walls clamping the edges of the coverings against said ring member.

5. A pair of case members formed with flanges, fabric coverings, a sheet metal band 75 enclosing said flanges and formed with case-gripping edges, said band formed with a longitudinal bead that projects inwardly between said flanges, the outer walls of said 80 bead engaging the interior faces of said flanges and having its inner walls compressed into clamping engagement with the edges of said coverings.

6. A tape measure case including flanged side members, a flange-enclosing rim formed with an internal bead that projects between the flanges, the walls of said bead distorted to tightly clamp the edges of said flanges against the inner face of the flange-enclosing rim.

7. A tape measure case including flanged side members, a flange-enclosing rim formed with an internal bead that projects between the flanges, the rim formed with lateral case-gripping edges, and the walls of said bead distorted to hold the edges of said flanges 95 against the inner face of the flange-enclosing rim.

In testimony whereof, I affix my signature.

EUGENE J. WITCHGER.
